UNITED STATES PATENT OFFICE.

JOSEPH H. ROMSEY, OF SOMERVILLE, MASSACHUSETTS, ASSIGNOR OF ONE-HALF TO NEIL MACDONALD, OF CAMBRIDGE, MASSACHUSETTS.

DESIGN FOR A SHOE.

SPECIFICATION forming part of Design No. 30,925, dated May 30, 1899.

Application filed May 1, 1899. Serial No. 715,240. Term of patent 14 years.

To all whom it may concern:

Be it known that I, JOSEPH H. ROMSEY, residing at Somerville, in the county of Middlesex and State of Massachusetts, have invented and produced a certain new and original Design for a Shoe; and I do hereby declare the following to be a full, clear, and exact description of the invention, such as will enable others skilled in the art to which it appertains to make and use the same.

The accompanying drawing shows a front elevation of the shoe.

As shown in the drawing, the leading and material feature of my design consists of a shoe having a front flap with a centrally-disposed band running up and down the middle

of the flap. Laterally disposed on the sides of the band are extensions, and the extensions are provided with rows of members of ball-and-socket fasteners.

Having thus described my invention, I claim as new and desire to secure by Letters Patent—

The design for a shoe, substantially as shown and described.

In testimony whereof I affix my signature in presence of two witnesses.

JOSEPH H. ROMSEY.

Witnesses:

NEIL MACDONALD,
HORACE VAN EVEREN.
